TWISTED STRING TOY

Reinhardt M. Wellner, Philadelphia, Pa.

Application October 6, 1950, Serial No. 188,789

3 Claims. (Cl. 46—63)

1

This invention relates to a twisted string toy. It is an object of the present invention to provide a twisted string toy wherein means are had which can maintain the operation of the twisted string toy by simple manipulation, as by the pulling of a trigger on a gun handle or of the squeezing of spaced handles whereby the rotation of the button or disc on the string will be maintained.

It is another object to provide in a twisted string toy, which is operated by a mechanical device, means for containing a plurality of the twisted string arrangements that permits and causes the rotation of these twisted strings about a center in order to display the different buttons throughout the use of the device.

Other objects of the present invention are to provide a twisted string toy which is of simple construction, inexpensive to manufacture, has a minimum number of parts, trigger operated, of pleasing appearance, compact and efficient in operation.

For other objects and for a better understanding of the invention, reference may be had to the following detailed description taken in connection with the accompanying drawing, in which:

Fig. 1 is a perspective view of the twisted string toy gun embodying the features of the present invention.

Fig. 2 is a front elevational view of the twisted string toy gun.

Fig. 3 is a vertical sectional view taken on line 3—3 of Fig. 1.

Fig. 4 is a longitudinal sectional view taken on line 4—4 of Fig. 1.

Figs. 5, 6 and 7 are respectively vertical transverse sectional views taken respectively on lines 5—5, 6—6 and 7—7 of Fig. 4.

Fig. 8 is an elevational view of one of the buttons which is spun.

Fig. 9 is a sectional view of the button taken on line 9—9 of Fig. 8.

Referring now to the figures, 10 represents a handle formed of two parts 11 and 12 cemented together and preferably of plastic or other suitable material. The handle is hollow and the separable parts have respectively opposing guide ways 13 and 14 in which can slide a trigger 15 having projections 16 and 17 entering respectively the guide ways 13 and 14 of the parts 11 and 12.

The handle has a forwardly extending projection 18 having an annular groove 19. On this projection there is fitted for rotation about the axis thereof a two-part sleeve 21 which is keyed through inwardly extending projections 22 to a

5 hollow shaft 23 that is journaled in the projection 18 of the handle. The sleeve 21 is held against axial displacement on the projection by a pin 24 that moves in the groove 19 and by which axial displacement of the forward end structure is prevented.

10 The outer end of the sleeve 21 has a reduced portion 25 into which the sleeve 23 extends. Extending into the outer end of the reduced portion 25 of the sleeve 21 is a shank 26 of a head member 27. This shank has a reduced portion 28 slidably in the hollow sleeve 23 and which has on its inner end and within the handle 10 a head formation 29. The trigger 15 has an upstanding yoke formation 31 that receives the reduced shank portion 28 and abuts the head formation 29 whereby to cause the head 27 to be worked or pulled toward the sleeve 21 as the trigger 15 is squeezed. The return movement of the head 27 is effected through a spring 32 that surrounds the small diameter portion 28 of the shank 26 and abuts the end of the sleeve 23. Accordingly, as the trigger is pulled and released, the head 27 will be moved toward the sleeve or head 21 and 15 returned to its extended position.

20 The sleeve 21 has three radially extending projections 32 that are respectively notched at their outer ends, as indicated at 33, to receive twisted string 34 that is looped at its end, as indicated at 35, Fig. 1, to fit over the end of the radially extending projection 32 and into the notch 33. There are three of these projections 32 which are circumferentially spaced from each other on the exterior of the sleeve 21.

25 The head 27 has similar projections 36 notched at their outer ends, as indicated at 37. These projections are slidably in the respective slots 38 on the outer end of the reduced portion 25 of the sleeve 21. By this means, rotation of the head 30 relative to the sleeve 21 is prohibited. Loop 38' on the opposite end of twisted string 34 extends over the end of the projection 36 and into the notch 37. There are three projections on both the sleeve 21 and the head 27 whereby provision is had for three twisted strings. On each twisted string is a button structure 39.

35 The button structure 39 is formed of two halves 42 and 43. The peripheral flange 44 of the half 43 is extended over the periphery of the half 42 whereby to hold the halves together. Internal reinforcing ribs 45 and 46 are respectively provided on the halves 42 and 43, as shown in Fig. 9. Within these halves there may be disposed balls 47 to impart a noise as the buttons 39 are spun.

40 The rear end of the inner sleeve or tube 23

has ratchet teeth 51 formed therein, Fig. 6, with which a ratchet element 52 pivotally connected, as indicated at 53, to a gear element 54, cooperates to step the forward assembly about the projection 18 of the handle. A spring 55 is anchored to the gear member 54, as indicated at 56, and its opposite end engages with the ratchet element 52, as indicated at 57, to urge the ratchet element 52 against the ratchet teeth formation 51. This ratchet element will prevent the reverse rotation of the forward assembly. A washer 54' is secured to the sleeve 23 to hold the gear 54 on the sleeve against rearward displacement therefrom. A shoulder 23' on the sleeve 23 holds the gear 54 against forward displacement thereon.

On the trigger 15 is a helical gear rack 58 that engages with helical gear teeth 59 on the gear member so that rotation will be imparted by the trigger to the gear 54 and the forward assembly. On the return movement of the trigger 15, the gear 54 will ratchet over the inner sleeve 23. If the button structures are of different color, they will be automatically displayed in sequence from the side of the gun. The button structure has small holes 60 and 61 extending through the halves thereof for receiving the string 34. As the trigger 15 is pulled in and released, the button structures will be rotated first in one direction and then in the other. The strings, by virtue of their being twisted, will have an elastic action to effect the spinning of the button structures. On each pull of the trigger the forward assembly will be rotated a part of a turn. This rotation will be continued on each pull of the trigger.

It will be seen that with this device hours of playing can be had without the need for replacement of the twisted strings. To replace these strings is a simple matter as the forward assembly can be retracted so that the strings can be placed over the projections thereon.

While various changes may be made in the detail construction, it shall be understood that such changes shall be within the spirit and scope of the present invention as defined by the appended claims.

What is claimed is:

1. A twisted string toy comprising a handle having a cylindrical projection thereon, a head member rotatably connected to the cylindrical projection and held against axial displacement therefrom, a second head member having a shank extending through the first head member, an inner sleeve fixed to the first head member, said shank extending through the inner sleeve, a trigger mounted in the handle for movement with respect thereto and connected to the shank of the second head member to move the second head member relative to the first head member so as to vary the spacing therebetween, a spring surrounding the shank of the second head member and abutting the end of the inner sleeve to normally urge the outward movement of the second head member from the first head member, each of said head members having respectively radially-extending portions circumferentially spaced from each other, twisted string button devices extending between aligned radially-extended portions of the head members, means carried by the

5
10
15

inner sleeve and responsive to the movement of the trigger for effecting the rotation of the inner sleeve and the head members as the trigger is pulled whereby the twisted string button devices will be rotated upon the handle.

2. A twisted string toy comprising a handle having a projection thereon, a head member rotatable on said projection, a second head member having a shank adjustable through the first head member, an inner sleeve surrounding said shank within said first head member and extending through the projection and into the handle, a trigger adjustable in the handle and connected to the shank to move the second head member, spring means surrounding the shank and reacting against the inner sleeve to extend the second head member relative to the first head member, means carried by the inner sleeve and responsive to the movement of the trigger to effect the rotation of the head members as the second head member is moved in and out, said head members having respectively projections extending radially thereon, twisted string button means extending between the projections to be operated thereon as the second head member is moved toward and away from the first head member.

3. A twisted string toy comprising a handle having a projection thereon, a head member rotatable on said projection, a second head member having a shank adjustable through the first head member, an inner sleeve surrounding said shank within said first head member and extending through the projection and into the handle, a trigger adjustable in the handle and connected to the shank to move the second head member, spring means surrounding the shank and reacting against the inner sleeve to extend the second head member, means carried by the inner sleeve and responsive to the movement of the trigger to effect the rotation of the head members as the second head member is moved in and out, said head members having respectively projections extending radially thereon, twisted string button means extending between the projections to be operated thereby as the second head member is moved toward and away from the first head member, and said operating means for rotating the head members comprising a helical gear, said inner sleeve having ratchet teeth, a ratchet element on said helical gear engageable with the ratchet teeth of the sleeve member to adjust the same, a rack on the trigger engageable with the helical gear to cause the rotation of the helical gear as the trigger is pulled.
